PURSE

Holfort Esdorn Bouges, New York, N. Y.

Application February 7, 1939, Serial No. 255,151

1 Claim. (Cl. 224—28)

The invention relates to a purse or the like and more especially to an arm fitting purse.

The primary object of the invention is the provision of a purse of this character, wherein it is built for wearing on the arm of a user, being securely held and minimizing liability of its loss, misplacement or theft as frequently happens when carried in the hand of such user.

Another object of the invention is the provision of a purse of this character, wherein during the wearing of the same it will not interfere with the garments of a wearer and is hidden from view in that the sleeve of the outer garment will cover such purse while being worn.

A further object of the invention is the provision of a purse of this character, wherein a single lock serves to fasten the said purse upon the arm of a person and also in a closed condition and in this manner is rendered theftproof, being upon the person, and does not lend discomfort in the wearing thereof when sleeping.

A further object of the invention is the provision of a purse of this character, which is simple in construction, readily and easily applied to the arm of a person for the wearing thereof, thoroughly reliable and efficient in operation, neat in appearance, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a perspective view of a purse constructed in accordance with the invention.

Figure 2 is a vertical transverse sectional view through the purse.

Figure 3 is a sectional view taken on the line 3—3 of Figure 2 looking in the direction of the arrows.

Figure 4 is a fragmentary plan view partly in section taken approximately on the line 4—4 of Figure 3 looking in the direction of the arrows.

Figure 5 is a fragmentary detail sectional view on the line 5—5 of Figure 2 looking in the direction of the arrows.

Similar reference characters indicate corresponding parts throughout the several views in the drawing.

Referring to the drawing in detail, A designates generally a purse constructed in accordance with the invention and comprises an arched body

10, preferably elongated, having permanently closed ends 11, sides 12 and outer wall 13, respectively, while the inner wall 14 constitutes a closure for the innermost open area of said body 10. This closure 14 is hinged at 15 for swinging movement, being held releasably latched by spring latches 16 engaging in keeper seats 17 therefor. The latches 16 are carried by the closure 14. Access can be had to the body 10 only through the inner side by the opening of 10, the closure 14 which carries a suitable finger nib 18 for convenience in the easy opening thereof.

Formed in opposite sides 12 of the body 10 preferably intermediate of the ends thereof are 15 the substantially half circular sockets 19, being walled throughout, and in the end walls 20 of each are suitably aligned openings 21, these accommodating spreadable locking bolts 22 and 23, respectively slidably coupled with each other 20 by a stem 24 having the head 25 fitting within a bore or guideway 26 in the bolt 23. Within this bore or guideway 26 is a tensioning spring 27 serving to spread the bolts 22 and 23 and releasably locking the same in the openings 21. These 25 bolts are slidably accommodated in pintle sleeve-like terminals 28 formed from sections 29 and 30, respectively, of a two-part separable arm-embracing strap or band. The section 29 has fitted thereon a combination lock 31 for the 30 fastening of the section 30 thereby and separably uniting the sections 29 and 30 of the arm band so that the purse therewith can be made secure upon the arm of a person for wearing thereon.

The bolts 22 and 23 are formed with finger grips 32, these being extended through a clearance 33 provided in the wall of each socket 19 so that the said finger grips 32 are accessible only at the interior of the body 10 for the release of the arm band or strap when it is required that the latter be separated from the body 10.

In the wearing of the purse upon the arm, when the arm band or strap embraces the same the closure 14 will be at the innermost side of the body 10 so that access to the purse can not be had from without the same except by manipulating the combination lock 31 for the separation of the sections 29 and 30 from each other and the removal of the purse from the arm whence the closure 14 will be free for the opening thereof and allowing access to the interior of the body 10.

It is impossible to detach the sections 29 and 30 from their fitting with the body 10 as the bolts 22 and 23 are only accessible from within the 55

body 10 and access had on the opening of the closure 14 in a manner as previously stated.

The bolts 22 and 23 fastening the sections 29 and 30 to the body 10 also function as pivots 5 for these sections so that the same may swing apart when unlocked from each other to the position shown by dotted lines in Figure 2, the closure 14 also being shown by dotted lines in said figure open or swung away from the body 10 of the purse for giving access to the interior thereof.

The purse is to be used in the usual manner for the carrying of valuables or other things.

The body 10 is preferably of shallow formation 15 and is of a curvature conforming to the curvature of the forearm of a person so that it can be comfortably worn upon the arm and will not protrude to an excessive degree therefrom during the wearing as well as eliminating interference 20 to the clothing, particularly the sleeve of an outer garment of a person.

The lock 31 serves to fasten the arm band or strap in embracing position on the arm of a wearer of the purse and also the holding of the

closure 14 in closing position thus rendering the purse practically theftproof. The wearing of the purse upon the arm of a person eliminates the hand carrying of such purse and liability of misplacement, which often happens during hand 5 carrying as well as the loss of the purse.

What is claimed is:

A purse for fitting an arm of a person, comprising a body forming a container open at the side next to the arm and having inset portions 10 forming recesses within the ends of said body, an arm-embracing element having separable sections, a closure for the open side of said body and confronting the arm-embracing element at the open side of the body, a sealing element for 15 separably securing the sections of the arm-embracing element together, and manually operated pin latches at the outer ends of the arm-embracing element, engageable in the walls of the recesses and accessible only from within said body 20 when in latching position through the open side of the latter.

HOLFORT E. BOUGES.
